B. JOHNSON.
FISHING CORK.
APPLICATION FILED JULY 9, 1920.

1,371,170.

Patented Mar. 8, 1921.

*Benjamin Johnson, Inventor,
attorney*

UNITED STATES PATENT OFFICE.

BENJAMIN JOHNSON, OF LEAVENWORTH, KANSAS.

FISHING-CORK.

1,371,170.

Specification of Letters Patent.

Patented Mar. 8, 1921.

Application filed July 9, 1920. Serial No. 394,935.

To all whom it may concern:

Be it known that I, BENJAMIN JOHNSON, a citizen of the United States of America, residing at Leavenworth, in the county of 5 Leavenworth and State of Kansas, have invented new and useful Improvements in Fishing-Corks, of which the following is a specification.

The object of the invention is to provide 10 an efficient construction of fishing cork and particularly an effective means whereby a cork may be readily attached to the line under conditions which while permitting the freedom of adjustment of the cork with 15 relation to the line to dispose the former at the desired distance from the hooks and sinker, will effectually lock the cork at the desired distance to guard against accidental displacement incident to the casting of the 20 bait; and with these objects in view, the invention consists in the construction and combination of parts, of which a preferred embodiment is shown in the accompanying drawings, wherein:—

25 Figure 1, is a side view of a cork embodying the invention, applied to a line.

Fig. 2, is a sectional view of the same.

Fig. 3, is a detail enlarged section of one of the line engaging means with the parts or 30 elements thereof disposed in line engaging relation.

Fig. 4, is a view similar to Fig. 3 with the parts arranged in line releasing relation.

The cork 10 may be of any preferred form 35 and construction of material with the usual terminal stems 11 provided for attachment to the line 12 except that said stems are of special construction to adapt the elements thereof to effectively engage the line so as 40 to lock the cork at the desired adjustment relative thereto. To this end, each stem consists of a core 13 which may consist of the terminal of a rod 14 extended axially through the cork and to be provided with a 45 transverse eye or line opening 15 and a sleeve 16 telescoped with relation to the core and fitted thereover with its inner reduced ends 17 fitted into a bore 18 in the end of the cork body where it is engaged by a coil 50 spring 19 arranged in said bore and surrounding the adjacent portion of the stem 14. Said sleeve is provided with a transverse eye or line opening 20 adapted for registration with the eye of the core to normally 55 hold it out of registration therewith by means of the spring 18. When the sleeve

is moved inwardly with relation to the core the counter action of the spring 18 by the application of the pressure as by the thumb or finger of the operator to the exposed end 60 of the sleeve, the eyes of the sleeve and the core are arranged in registration as indicated in Fig. 4 to permit of the threading of the line 12 therethrough, but upon releasing the said sleeve and the consequent 65 outward movement thereof by the action of the spring the eyes are dis-aligned and the portion of the line extending therethrough is clamped to lock the cork in the selected 70 adjustment. Obviously by pressing the 75 sleeves to both ends of the cork simultaneously to release the line, the cork may be moved freely with relation to the line to secure the desired positioning thereof with reference to the hooks or the sinker and upon the release of the pressure upon the sleeves, the cork will be held in place under such conditions as to resist any tendency to movement or displacement due to the casting 80 of the line.

The eyes in the core and sleeve may be effectively fitted with rubber or other linings 21 forming cushions to frictionally engage the line while preventing the chafing thereof.

The invention having been described, what is claimed as new and useful is:—

1. A cork having a line attaching stem consisting of telescoping members provided with registerable line receiving eyes and 90 means for yieldingly holding one of said members in position to clamp a line extended therethrough.

2. A cork having a line engaging stem consisting of slidably related telescoping 95 members provided with registerable line receiving eyes and a spring for yieldingly holding one of said members with the eyes out of alinement.

3. A cork having a line engaging stem 100 consisting of a core and a sleeve fitted to slide upon the core and yieldingly actuated by a spring, said core and sleeve being provided with registerable line receiving eyes.

4. A cork having a line engaging stem 105 consisting of a core and a sleeve fitted to slide upon the core and yieldingly actuated by a spring, said core and sleeve being provided with registerable line receiving eyes, having cushioning linings.

In testimony whereof I affix my signature.

BENJAMIN JOHNSON.
